UNITED STATES PATENT OFFICE.

CHARLES F. KETTERING, OF DAYTON, OHIO, ASSIGNOR TO THE DAYTON ENGINEERING LABORATORIES COMPANY, A CORPORATION OF OHIO.

CIRCUIT-BREAKER INDICATING DEVICE.

1,336,142.

Specification of Letters Patent.

Patented Apr. 6, 1920.

Application filed August 20, 1914. Serial No. 357,644.

To all whom it may concern:

Be it known that I, CHARLES F. KETTERING, a citizen of the United States of America, residing at Dayton, county of Montgomery and State of Ohio, have invented certain new and useful Improvements in Circuit-Breaker Indicating Devices, of which the following is a full, clear, and exact description.

10 The subject of this application is an improvement in apparatus for use with an electric circuit and designed to indicate the existence therein of an abnormal flow of current. The invention is applicable to electric 15 circuits of wide variety, but it was especially designed for use in motor vehicles in connection with the circuits therein, including a dynamo, a secondary battery, and ignition device, lamps and other elements, and 20 the illustration herein given will be confined to such uses.

It is well known that in circuits of this nature, it is customary to insert one or more fuses, which, under conditions of abnormal 25 current flow are blown out, thus interrupting the circuit and protecting the working devices therein from injury or destruction. The main object of the present invention, however, is to provide a means which will 30 prevent the burning out of the working devices, and at the same time afford an unmistakable indication of the existence of abnormal conditions, to enable an attendant to take immediate steps to correct them.

35 To this end the invention consists in an improved form of circuit interrupter which, when affected by an abnormal current, will operate to intermittently break the circuit as long as the conditions exist which endanger the devices therein, and likewise give the operator some clear indication of this condition.

It is therefore among the objects of the present invention to provide an overload indicating device in the form of a circuit breaker which will make and break the circuit successively and thus give warning of the overload condition by means of successive flickering of the lights or an audible 45 clicking of the interrupter mechanism; furthermore, for the best results, the successive breaks and makes should be retarded or spaced apart sufficiently to give a more pronounced effect of the flickering, or to the

audible clicking; and in addition, to reduce 55 the current output as much as possible during the operation of the interrupter, so that although visible or audible indication is given to denote trouble on the line, yet this indication will be at the expense of small 60 current output.

Further objects and advantages of the invention will be understood from the description which follows, and by reference to the accompanying drawings, in which the device 65 is shown in its preferred form.

Figure 1 is a diagram of the circuit connections, showing also the relations and illustrating the functions of the several parts of the apparatus.

Fig. 2 is a view in side elevation of the device embodying the invention.

Fig. 3 is a top plan view of the apparatus shown in Fig. 2.

Fig. 4 is a cross-sectional view taken on 75 the line 4—4 of Fig. 2.

As above stated, the illustration is of an electric system for motor vehicles in which 20 is the dynamo, 21 the secondary battery in circuit therewith through wires 23, 24 and 80 34, or otherwise, in any suitable manner, 33 the lighting circuit and 37 the primary coil of the ignition device, in parallel with the lighting circuit by wires 35, 38 and 40, the latter forming a circuit which includes also 85 the timer or circuit interrupter 39. The main or work circuit in the present instance is connected at the point 28, with both the generator and the battery circuits. The circuit comprises the wire 30, which leads 90 to the current interrupter or indicating device 31, to be hereinafter described in detail.

The wire 32 tends to complete one side of the lighting circuit and connects to one side of the lamps, while the other side of 95 the said circuit and the main circuit are completed by means of the wire 34. The ignition circuit by the wires above mentioned is between the points 36 and 41 of the main circuit.

100 The device for interrupting and protecting the circuits of the present case is structurally illustrated in Fig. 2, and is shown as included in the path of the main circuit between the dynamo and the battery and other 105 working elements of the ignition, lighting and other circuits. It will, however, be understood that, if so desired, one of these de

5 vices may be combined with each of the work circuits, in which event each will be equipped with some means to give a different indication, or signal, when abnormal 10 conditions occur in the respective circuits, in order to show the specific circuit wherein 15 these conditions exist.

10 A detailed description of the interrupter will now be given. The wire 30, which is connected directly to the wire 24, and also to the wire 23, leading respectively from the battery and generator, is connected with the heavy series coil 45 of the indicating device or interrupter 31. This coil 45 is wound 15 about a core 46, and is also connected with the fine wire coil 47, by means of the branch connection 48. The windings 45 and 47 and the core 46, constitute an electromagnet, which is adapted to control the operation of 20 the armature 49.

25 The heavy winding 45 is electrically connected with the plate 50 in any suitable manner, which in turn is so mounted that it is in contact with the plate 51. This plate 51 is provided with a supplemental contact plate 52, which is normally in contact with the plate 54; this plate 54 connecting with the wire 32 of the main circuit.

30 It has been explained that the fine winding 47, which may be termed the retarding coil, has electrical connection with the coil 45, by means of the branch wire 48. The opposite end of this coil 47 is electrically connected with the auxiliary contact plate 35 55, which in turn is actuated by the operation of the armature 49 and the consequent engagement of this auxiliary spring contact plate by the plate 51. The arrangement of the auxiliary plate 55 and the contact plate 40 51 is such that a slight wiping contact will occur when the armature 49 is operated to move the above mentioned plates 51 and 55, respectively.

45 A small shunt 56, the resistance of which increases with its temperature, such as iron wire, is connected with the wire 30 and the contact plate 50, in any suitable manner, and is adapted to practically short circuit the heavy winding 45, except under certain 50 conditions which will be fully explained hereinafter.

55 The shunt element 56 and the winding 45 are so proportioned in resistance that substantially the required amount of current to properly operate the lighting, ignition and accessory circuits, can be passed by them, without affecting other elements of the interrupter.

60 If, for any reason, a short circuit should inadvertently occur in the lighting, ignition or accessory circuits, an abnormal current would flow through both the shunt element 56 and the winding 45. The shunt element having this increased current flowing there- 65 through, will quickly heat up and thereby

acquire a much higher resistance. This would cause a still greater proportion of the current to flow through the windings 45, the circuit being completed to the work circuit, via contact plate 50, and plates 51, 52 and 70 54 to the main wire 32.

75 A spring 58 is so constructed that the tension will hold the armature 49 in unattracted position, as long as the flow of current through the shunt element 56 and winding 45 remains normal. As soon as an increased current (to a predetermined amount according to the design) is caused to flow 80 through the windings 45, as has been heretofore described, the tension of the spring 58 85 will be overcome, and the armature 49 will be attracted, causing the contact between plates 50 and 51, 52 and 54, to be broken.

90 By referring to Figs. 2 and 3, it can be seen that the auxiliary contact plate 55 is riveted to the contact plate 51 in such manner that no movement will be transmitted to said contact plate 55, until the contact plate 51 moves far enough to force the plate 55 out of contact with the plate 54. This results in the contact between 55 and 54 being broken at a time slightly subsequent to the above described breaking of the contact at the points 50, 51, 52 and 54; and a consequent making of the contact at the points 95 54 and 55, just prior to the making at the other points, when the armature 49 again moves downward toward its normal position.

100 When the different elements of the interrupter are in their normal positions; as shown in Figs. 1 and 2, the auxiliary contact 55, being made of any suitable resilient conducting metal, is slightly under tension. Thus, when the contact plate 52 is freed out 105 of engagement with the plate 54, it carries said plate 55 to disconnect from plate 54, with a sliding movement, preventing oxidizing or pitting at the point of contact.

110 In Fig. 3 the shape of the unitary double contact plates 51 and 52 is such that both of said contacts together form the letter **U**, and said contacts are being fastened to and insulated from the armature 49 in any suitable manner. The armature is pivoted to the 115 frame 59 at 60.

120 The **U**-shaped double contact plate 51 and 52 as shown in Fig. 3, has the base portion of the **U** located at the left in Fig. 3, and fastened to the armature 49 so that in the manner in which Fig. 3 is illustrated, the **U** is lying on one side with the base at the left and with one of the arms 51 extending to the right over the contact plate 50, while the other arm extends similarly to the right 125 over the contact plate 54, but as shown, this arm is almost all concealed by the overlying contact plate 55.

130 In Figs. 3 and 4, the stationary contact plates 50 and 54, coöperating respectively

with the movable double contact plates 51 and 52, are shown as being held in position by the insulated screws 63 and 64. The terminal plates, having suitable terminal 5 leads 65 and 66 are also shown in Fig. 3.

The shunt element 56 is shown held in position by the screws 63 and 64, one end contacting with the stationary contact plate 50, the other with the terminal and drop 10 lead 66 and 66^a respectively.

The leads 61 and 62 in Fig. 4 are the two extremities of the heavy winding 45, one being connected to the stationary contact plate 50, the other to the drop lead 66^a.

15 As has already been described, when an abnormal or overload current flows through the main circuit, the result is to heat up the iron wire 56 and thereby throw enough current through the shunted winding 45 of the 20 circuit breaker, as to operate the armature 49 and break the main line circuit at the points 50, 51, 52 and 54.

But it will be observed that the auxiliary winding 47 of the circuit breaker is still in 25 the main circuit, that is, the current can still flow through the winding 47, wire 57, plates 55 and 54, out to the main line 32. But this coil 47 is thereby still acting to attract the armature 49 and thus break the circuit 30 at the second set of contact points, namely, the points 54 and 55, and when this occurs, the main line circuit is completely broken. Whereupon, the core 46 will become demagnetized and the armature 49 will 35 then, under its spring tension, tend to move back toward normal position.

By using the additional or retarding coil 47, a sluggish or retarding effect is exercised upon the operation of the armature 40 49. Thus, after the main circuit has been completely broken at both sets of make and break points, the movement of the armature 49 toward the right in Fig. 1, will first partly reestablish the main circuit at the 45 make and break point 54-55. This establishes the circuit through the high resistance coil 47, which in turn exercises a pulling effect upon the armature, to retard its further movement to the right; so that all 50 though the armature may continue its movement to the right and thus make the circuit at the other make and break point 50, 51, 52, 54, this complete making of the main circuit is retarded by the action of the 55 coil 47.

The result therefore would be that the armature 49 vibrates at a slower rate, and thus makes a more distinctive clicking sound than would be the case if it vibrated solely 60 under the influence of the coil 45 and a single make and break point.

Furthermore, by having the second interrupter coil 47 of high resistance, less current is used when this coil is in circuit alone, 65 by the closing of the second make and break

point 54-55. Likewise, less resultant current is used if the armature 49 is retarded in its re-making movement.

Thus, the circuit breaker may be said to comprise a main make and break point, and an auxiliary make and break point, and these are operated successively by the armature, so that the breaking at the main point still leaves the auxiliary point operative under the control of its auxiliary interrupter 70 coil, (the coil 47), which exercises a retarding effect when both make and break points are successively and intermittently operated, and at the same time there is a reduction in the resultant current utilized by the 80 circuit breaking operation, as above explained.

If therefore, there is enough resultant current to illuminate the electric lamps on the work circuit, these lamps will indicate the 85 presence of the trouble by flickering, and at least the interrupter armature will give audible indication by the successive clicking sound. Furthermore, the flickering or the 90 audible clicking will be spaced apart to give a more appreciable signal, by reason of the retarding effect spoken of.

It will of course be understood from the construction described that it is the vibratory movement of the armature which 95 causes the audible clicking or tapping referred to, as for example the striking of the armature against the core.

From the above description, it will be seen that the interrupter is effective, not 100 only as to the lighting circuit, but also as to the ignition circuit. However, under some circumstances, it may be desirable to have the interrupter effective only with respect to the lighting circuits. When this is the 105 case the wire 40 is disconnected from wire 32 and is connected with wire 24.

While the form of mechanism herein shown and described constitutes a preferred form of embodiment of the present invention, it is to be understood that other forms might be adopted, all coming within the 110 scope of the claims which follow.

What I claim is:—

1. In a circuit-breaker indicating device, 115 having main contacts and auxiliary contacts in shunt therewith; means for opening the main contacts upon excessive current flow; and means brought into action by the operation of said first means for extending the 120 opening movement of said main contacts and then opening the auxiliary contacts.

2. In a circuit-breaker indicating device, 125 a series coil; an armature in operative relation thereto; main series contacts operated by said armature; a circuit in shunt with said main contacts, said circuit containing auxiliary contacts operated by said armature; and an auxiliary coil operatively related to the latter.

3. In a circuit-breaker indicating device having main contacts and auxiliary contacts in shunt therewith; means for opening the main contacts upon excessive current flow; 5 means brought into action by the operation of said first means for extending the opening movement of said main contacts and then opening the auxiliary contacts; and means for returning the circuit breaker 10 to normal position after each actuation upon excessive current flow.

4. In a circuit breaker indicating device, the combination with the main work circuit, of main and auxiliary make-and-break contacts in said circuit; an electro-magnet operated by the main circuit current; means connected with said main and auxiliary contacts and operated intermittently by said magnet to break the main circuit by quick 15 successive breaks of first the main contact and then the auxiliary contact and then make said main circuit; and a thermal resistance shunted around said magnet, operating upon an abnormal flow of current in 20 the main circuit to send increased current through the coils of the magnet whereby to 25 operate the latter.

5. In a circuit-breaker indicating device, the combination with a main circuit and a 30 circuit-breaker means for intermittently breaking said circuit upon an abnormal flow of current therethrough; of an electrical device normally short-circuiting the circuit breaker but operated by an abnormal flow of 35 current to send current through the circuit breaker to operate the latter.

6. In a circuit-breaker indicating device, the combination with a main circuit and circuit-breaker means for intermittently 40 breaking said circuit upon an abnormal flow of current therethrough; said circuit breaker means including an electro-magnet and armature with auxiliary provisions for operating upon said armature to delay its normal 45 time of re-making of said main circuit.

7. In a circuit breaker indicating device, the combination with a main circuit, of a circuit breaker coil wound upon a core; an armature operated by the magnetic effect 50 of said core to intermittently break the main circuit when an abnormal flow of current passes through said circuit breaker coil; and means for setting up an auxiliary magnetic effect in the core after the main circuit connection is broken by said armature, whereby 55 the movement of this armature to its nor-

mal position to completely close the main circuit connection will be retarded.

8. In a circuit-breaker indicating device, the combination with a main circuit; of circuit-breaking means in said circuit comprising a core; an armature mounted in vibrating relation to said core and adapted to produce a signal upon striking said core; a spring tending to move said armature away from said core; and electromagnetic devices adapted on passage of abnormal flow of current first to attract said vibrating armature to open the main circuit and thereafter to resist the action of said spring in returning said armature whereby to retard the closing of the main circuit. 60 65 70

9. In a circuit-breaker indicating device, the combination with a main circuit; of circuit-breaking means in said circuit comprising a core; an armature mounted in vibrating relation to said core and adapted to produce a signal upon striking said core; a spring tending to move said armature away from said core; electro-magnetic means 75 adapted to attract said armature to open said main circuit; and auxiliary electromagnetic means rendered operative by said first named electromagnetic means for resisting the return of said armature and consequently retarding the closing of said main circuit. 80 85 90

10. In a circuit breaker indicating device, the combination with a main work circuit of a first parallel circuit comprising a thermal resistance as one branch and a main magnet winding as the other branch; a second parallel circuit comprising main make-and-break contacts in one branch and a second branch including an auxiliary magnet winding and auxiliary make-and-break contacts, said parallel circuits being in series in said main work circuit; a magnet core co-operating with said magnet windings; an armature cooperating with said core; a spring tending 95 to maintain said armature in unattracted position; and means co-operating with said make-and-break contacts and armature whereby to separate first the main contacts and then the auxiliary contacts as the armature is moved toward the magnet core. 100 105

In testimony whereof I affix my signature in the presence of two subscribing witnesses.
